(57) **CLAIM**

The ornamental design for an aerosol container, as shown and described.

DESCRIPTION

FIG. 1 is a top perspective view of a first embodiment of an aerosol container;

FIG. 2 is a bottom perspective view of the first embodiment of the aerosol container;

FIG. 3 is a left side elevational view of the aerosol container of FIGS. 1 and 2;

FIG. 4 is a right side elevational view of the aerosol container of FIGS. 1 and 2;

FIG. 5 is a top view of the aerosol container of FIGS. 1 and 2;

FIG. 6 is a bottom view of the aerosol container of FIGS. 1 and 2;

FIG. 7 is a front elevational view of the aerosol container of FIGS. 1 and 2;

FIG. 8 is a rear elevational view of the aerosol container of FIGS. 1 and 2;

FIG. 9 is a top perspective view of a second embodiment of an aerosol container;

FIG. 10 is a bottom perspective view of the second embodiment of the aerosol container;

FIG. 11 is a left side elevational view of the aerosol container of FIGS. 9 and 10;

FIG. 12 is a right side elevational view of the aerosol container of FIGS. 9 and 10;

FIG. 13 is a top view of the aerosol container of FIGS. 9 and 10;

FIG. 14 is a bottom view of the aerosol container of FIGS. 9 and 10;

FIG. 15 is a front elevational view of the aerosol container of FIGS. 9 and 10; and,

FIG. 16 is a rear elevational view of the aerosol container of FIGS. 9 and 10.

The broken lines in the drawing depict portions of the aerosol container that form no part of the claimed design.

1 Claim, 8 Drawing Sheets
